(57) **CLAIM**

The ornamental design for a wall-mount magazine rack, as shown and described.

DESCRIPTION

FIG. 1 is a front and top perspective view of first embodiment of a wall-mount magazine rack, showing my new design;

FIG. 2 is a rear and bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is a front and top perspective view of second embodiment of the wall-mount magazine rack;

FIG. 10 is a rear and bottom perspective view thereof;

FIG. 11 is a front elevation view thereof;

FIG. 12 is a rear elevation view thereof;

FIG. 13 is a left side elevation view thereof;

FIG. 14 is a right side elevation view thereof;

FIG. 15 is a top plan view thereof; and,

FIG. 16 is a bottom plan view thereof.

The broken lines in the figures illustrate portions of the wall-mount magazine rack that form no part of the claimed design.
